UNITED STATES PATENT OFFICE.

ARTHUR W. BERNE, OF NEW ORLEANS, LOUISIANA, ASSIGNOR TO BROWNLEE
W. TAYLOR, OF SAME PLACE.

FARE-COLLECTOR.

SPECIFICATION forming part of Letters Patent No. 431,431, dated July 1, 1890.

Application filed February 10, 1890. Serial No. 339,959. (No model.)

To all whom it may concern:

Be it known that I, ARTHUR WELLESLEY BERNE, a citizen of the United States, residing at New Orleans, in the parish of Orleans and State of Louisiana, have invented certain new and useful Improvements in a Fare-Collector; and I do declare the following to be a full, clear, and exact description of the invention, such as will enable others skilled in the art to which

it appertains to make and use the same.

My invention relates to fare-collectors in which the fare is placed within a portable case by the passenger and passes by gravity into a receptacle at the end of the case opposite to that in which it was deposited; and it consists in certain improvements of such a collector whereby it is impossible to remove the fare from the receptacle after it has been deposited therein without separating the case and receptacle, and whereby the mouth of the receptacle is automatically closed and locked when the two are separated, thus requiring that the same be unlocked before it can again be opened for removing the fares. These objects are attained by the construction as will be hereinafter more fully set forth, and which is shown in the accompanying drawings, in which—

Figure 1 is a perspective view of my improved fare-collector closed and partly broken away. Fig. 2 is a longitudinal sectional view of the same. Fig. 3 is a broken perspective view of the connecting portions of the collector partly separated from each other.

In the drawings, A indicates the receiving-case, which may be of any desired material, and to which a bag or receptacle S is attached. The case is provided with a glass front and a metallic plate C, which is hinged within its upper portion and extends diagonally down through the case to its end. A spring 3 behind the plate keeps its lower end against the wall of the case opposite to the one near which the upper end is pivoted. When a passenger deposits a fare in the mouth of the collector E, which is preferably funnel-shaped, it passes down between the plate and the glass front, where it can be seen by the conductor, and if found correct the lower end of the plate is pushed away from the wall by

means of the thumb-piece D, which projects from the plate out through the side of the case, and the fare then passes down into the receptacle S. As soon as the pressure is removed from the thumb-piece the spring 3 55 brings the lower end of the plate back into its original position, and the collector is ready to be presented to another passenger for a fare.

To prevent the possibility of the fare being 60 taken out at the mouth of the case after it has been deposited, and before it can be passed down into the receptacle, I provide the upper portion of the case with two plates or gravity-traps 1 and 2, hinged upon opposite sides of the case, so that if the case should be inverted to let the fare slip down and out of the mouth E the traps will swing in opposite directions to each other and close the passage so completely that it would be impossible for the fare to get past them. After the fare has entered the receptacle its return into the case is prevented by the gravity-trap or plate 4, which is hinged within the case below the plate C, which as soon as the case 75 and receptacle are inverted to let the fare pass back into the case will swing on its pivots, and thus close the passage between the receptacle and the case.

The receptacle can be secured to the case 80 in any suitable manner; but I have generally provided it with a metallic case or mouth O, which I shall call a "slide," and into which the lower end of the upper case A is inserted where the two are joined together. The bag 85 or receptacle S, which is preferably made of cloth, leather, or other suitable material, is secured to the lower end of the slide by means of a metallic band R, between which and the slide the upper edge of the receptacle is 90 clamped by means of ordinary rivets through them. The slide and case are secured together by means of a catch M, which is secured to a spring K within the slide. This catch projects through the case, and when the case and 95 slide are connected it projects through a slot M² in the slide and prevents the slide from being removed until the catch has been withdrawn, which is accomplished by pushing in on the pin or projection L, which is also se- 100

cured to the spring and projects out through a semicircular opening L' at the top of the slide. As the case and slide can be separated by pressing upon the pin L, the contents of the receptacle could be taken out by simply separating the case and slide, if there were no means to prevent it. To prevent the removal of the contents of the receptacle in this manner, I provide the slide with the plate T, which is secured to the side at one end by means of the pivots 5, and has its opposite end provided with a lug or projection 7, which can be made to engage with a lock P on the other side of the slide by swinging the plate into a horizontal position. As the lock P is on the outside of the slide, a slot Q is cut in the wall of the slide, through which the lug 7 can project as it is swung up to engage with the lock.

In order to make the plate close automatically when the case and slide are separated, the plate is connected with the lower end of the case by means of a link or rod U, which is provided with the lugs or pivots 6 and 8 at its ends, the lower one of which 6 engages with the plate, and the upper one 8 fits within a hole H in the lower end of the case. The side of the plate or trap T is cut away, as at V, and the lower end of the side of the case is cut away at G for the reception and operation of the link without binding between the case and slide when they are put together. This link is of such a length that when the lower end of the case is inserted into the slide as far as it will go, the plate T is held flat against one side of the slide, which leaves an open passage between the case and receptacle S; but as soon as the case and slide are drawn apart the link will draw the plate up into a horizontal position, so that it will stand directly across the mouth of the receptacle and close the passage through the slide. When it is drawn up into this position, the lug 7 enters the slot Q and is automatically secured by the lock P. The case can then be removed from the slide by withdrawing the pivot 8 from the hole H, or, rather, by taking the case off of the pivot, which can be done by moving the case and slide in opposite directions. A flange F around the lower portion of the case A engages with the top of the slide when the two are put together and prevents their moving upon each other too far.

When a conductor returns from a trip, he hands the collector over to the proper person, who separates the receptacle from the case by pressing in on the pin, as above described, and then unlocks the plate T and releases it, so that it will fall down at the side of the slide, and then by inverting the receptacle

the contents may be removed. The case and receptacle are then again united, when the collector is ready for further use. In this manner when the fare is deposited it is virtually in the possession of the company, as it is an impossibility for the conductor to gain access to it in any manner. When he receives the collector from the proper officer, the conductor is given enough money to make change, and as the passenger deposits the fare in the mouth of the case he has no opportunity whatever of keeping any or a portion of it, as it does not get into his possession at any time except within the collector.

Having described my invention, what I claim is—

1. In a fare-collector, the combination, with a case, of a receptacle detachably secured to its lower end, and a plate within the mouth of the receptacle attached to the lower end of the case; whereby the removal of the case swings the plate and closes the receptacle; substantially as specified.
2. In a fare-collector, the combination, with a case, of a receptacle having a slotted slide secured to its upper end, a lock upon the slide, a plate pivotally secured within the slide and having a lug on its free end to engage with the lock, the projection passing through the slot, and a link for connecting the plate with the lower end of the case; substantially as specified.
3. In a fare-collector, the combination, with a case the lower end of which is cut away and provided with a hole, of a receptacle having a slide secured to its upper end, a plate pivotally secured within the slide, the side of which is notched or cut away, and a link the upper end of which is secured to the case and fits within the cut-away portion, and the lower end is secured to the plate and fits within the notch at its side; substantially as specified.
4. In a fare-collector, the combination, with a case having a flange around its lower portion, of a receptacle having a slide secured to its upper end, said slide having a slot and an opening at its upper end, a spring within the lower end of the case, having a pin and a catch secured thereto, which pass through and engage with the slot and the opening in the slide when the collector is closed, and an automatically-locking plate pivotally secured within the slide and connected with the case; substantially as described.

In testimony whereof I affix my signature in presence of two witnesses.

ARTHUR W. BERNE
